(57) **CLAIM**

The ornamental design for a set of cables, as shown and described.

DESCRIPTION

FIG. 1 is a left elevational view of two cables in accordance with the present invention. The portion in broken lines indicates connectors which provide coupling between cable ends and which form no part of the claimed design.

FIG. 2 is a front elevational view of the FIG. 1 invention.

FIG. 3 is a right elevational view of the FIG. 1 invention.

FIG. 4 is a rear elevational view of the FIG. 1 invention.

FIG. 5 is an enlarged view of one end of one of the cables shown in FIG. 2.

FIG. 6 is a perspective view of the FIG. 1 illustration; and, FIG. 7 is an enlarged perspective view of a cable end shown in FIG. 5.
